Fig. 24

A technical diagram of a mechanical assembly. At the top, a horizontal plate features a central slot with a stepped profile. A vertical plate is positioned below the slot. Several components are labeled with numbers: 87 is on the left side of the top plate; 86 is at the top right, pointing to a slot; 85 is at the far right; 96 is on the left side of the lower vertical plate; 98 is on the left side of the lower horizontal plate; 95 is on the right side of the lower horizontal plate; 99 is at the bottom left; and 83 is at the bottom right. The diagram uses lines to connect the labels to their respective parts.

UNITED STATES PATENT OFFICE.

LEWIS E. MORRISON, OF NEWARK, NEW JERSEY, ASSIGNOR TO HIMSELF AND S. HAINES PLUM, 2D, OF MADISON, NEW JERSEY.

PRINTING MACHINE.

Substitute for application Serial No. 300,702, filed May 29, 1919. This application filed May 23, 1921.
Serial No. 473,271.

To all whom it may concern:

Be it known that I, LEWIS E. MORRISON, a citizen of the United States, and resident of Newark, in the county of Essex and State 5 of New Jersey, have invented certain new and useful Improvements in Printing Machines, of which the following is a specification.

This invention relates to improvements in 10 printing presses. More particularly the several improvements embodied in this invention are designed for use on job printing presses of the Chandler and like types, though not expressly limited thereto.

15 The object of the invention is to provide certain novel, useful and practical improvements and apparatus adapted to be attached to a job printing press with the object of converting the ordinary type of such press, 20 which is hand-fed and hand-delivered, into an automatic machine in which the separating of the paper, the feeding and delivering are performed automatically.

25 More particularly one object of the invention is to provide an improved separating mechanism for separating the sheets or other matter to be printed, and to feed the separated paper to the platen in a novel and improved manner. Another object of the 30 invention is to provide an improved gripping and delivery mechanism for automatically removing the printed matter from the platen. Still another object is to provide a jogging or stacking mechanism, operated 35 in a novel and improved manner. Another object is to provide improved means for tripping the press in the event that either the separating or the gripping mechanism fails to act or are prevented from operating 40 normally.

It is an important feature and object of 45 the invention to so arrange, design and construct the several mechanisms, and others, referred to, that they may be attached to an ordinary printing platen press without requiring much, if any, alteration of the machine and whereby the entire operation of printing becomes automatic.

50 It is an equally important feature and object of the invention to arrange the several mechanisms referred to in such a manner

that the machine may be quickly converted from an automatic machine into a hand-fed and hand-delivered press and vice versa.

55 This application is a substitute for the abandoned application for the same invention filed May 29, 1919; Serial Number 300,702.

With the foregoing and other objects in 60 view, the invention comprises such features, arrangements and combinations of parts and elements as are hereinafter described and claimed, while reference is had to the accompanying drawings in which

65 Fig. 1 is a general side view of a platen printing press embodying the invention with details omitted;

70 Fig. 2 is a front view of the press looking in the direction of arrow 2 in Fig. 1;

75 Fig. 3 is a sectional detail view of the separating nozzle shown in position on top of the pile of sheets just prior to the separation of a sheet from the pile;

80 Fig. 4 is a similar view showing the nozzle in position as picking up the separated sheet;

85 Fig. 5 is a front view of the nozzle looking in the direction of arrow 5 in Fig. 3;

80 Fig. 6 is a bottom view of the nozzle;

Fig. 7 is a detail view of a modified nozzle;

Fig. 27 is a view of the tripping means looking in the direction of the arrow 27 in Fig. 26;

Fig. 28 is a sectional view of parts shown in Figs. 26 and 27;

Fig. 29 is a detail view of the tripping link;

Fig. 30 is a view on line 10—10 of Fig. 29;

Fig. 31 is a diagrammatic view of the tripping mechanism and associated parts;

Fig. 32 is a detail view of parts of the electrical connections;

Fig. 33 is a detail view looking in the direction of arrow 33 in Fig. 31.

Referring to Fig. 1, which illustrates the left side of the press, the front of the press is denoted by the numeral 1 and the rear by the numeral 2 for the purpose of locating the several parts of the mechanisms.

The press as illustrated in outline only is a typical job or platen press. The frame of the press is denoted in general by the reference numeral 3. 4 is the driving shaft; 5 the platen pivot; 6 the platen; 7 the form member pivoted at 8. 9 indicates the linking mechanism. 10, 10 is the connecting rods and 12 the platen locking cam. 13 is the tripping means normally on presses of this type and 14 is the tripping lever. All of the aforesaid parts their construction, function and operation are well known in the art and need no further illustration or description.

The feed table, transfer mechanism and gripping mechanism are assembled to form a separate unitary structure or element which is supported, constructed and operated as follows.

On the left side of the press and suitably secured to the frame 3 is a bracket 15, Figure 8, having a rearwardly inclined upright 16 and a depending forward portion 17.

Similarly on the right side of the press there is a bracket 18, Fig. 2, having an upright 16 and a depending portion 17. In addition, the bracket 18 has a forwardly inclined upright 19 and a cam support 20. On the upright 19 there is pivoted at 21 a bracket 22 which forms a supporting ledge at 23 for the feed table 24. The feed table, see Fig. 18, is in the form of an open framework pivoted at 25 to the said support 22. The feed table rests normally on the said two uprights 16, 16 which are provided with shoulders 26, 26 for this purpose. It is further adapted to be raised or swung in a vertical plane on the pivot 21 as shown dotted in Fig. 9, and after having been thus raised, the feed table is movable laterally or may be swung horizontally on the pivot 25 as seen in Fig. 18.

The feed table and the bearing support 22 are swung vertically as one piece by the following means, see Fig. 9. 28 is a curved lever pivoted at 29 to the bearing 22 and having a tail stop 30. 31 is a link pivoted at 32 to the lever 28 and at 33 to the bracket 18. 34 is a stop pin in the link 31. The parts are in the normal position as shown in Fig. 9 where it will be observed that the lever 28 rests against the stop pin 34 and the pivot 32 is below the level of the pivots 29 and 33 so that there is a dead lock as will be understood. When it is desired to raise the feed table, the lever 28 is pulled forward and downward into the dotted position shown, whereby the bracket 22 is moved rearward as shown and the feed table lifted off the uprights 16, 16 and into horizontal position as indicated. When the lever 28 is moved into its lowermost position, the tail stop 30 abuts the stop pin 34 on the under side thereof, and the pivot 29 now comes between the pivots 32 and 33 and is deadlocked as indicated. Thereafter the feed table may be swung horizontally to the right as shown in Fig. 18 and a hand feed board 36 may be placed in a socket 37 and the press may then be hand-fed and hand-delivered. By movements in the opposite direction, the feed table is brought back laterally over the frame and is then lowered to rest on the brackets 15 and 18 on the parts 16, 16 thereof.

On top of the feed table rests the paper board 40, Fig. 8, which comprises the board 40 supported in an inclined position by means of its sides or legs 41, 41. Each side is provided with a slotted lug or foot 42, Fig. 9, through which passes a screw 43. To the feed table is secured a lug 44 having a slot 45. 46 is a shaft which passes through the slots 45 and which has an eccentric portion 47 journaled in the side 41 outside of which it carries a hand wheel 48. By first loosening the screws and then turning the hand wheels 48, the shaft 46 is rotated to throw the eccentric portions 47 so as to ad-

just the position of the paper board in the feed table. 49, 49 are paper side guides and 50, 50 are paper rear stops or stops for the leading edge. All of the said stops are adjustable as shown.

Separating and feeding means.

The top sheet is separated from the pile of paper 52 and fed to the platen by the suction nozzle 53. See Figs. 3 to 9 inclusive, also Fig. 1. The nozzle is carried on a supporting rod 54 and is adjustably secured thereto by a set screw 55. The rod is fixed to a nozzle arm 56. To the connecting rods 15, 10 there is secured a U-shaped bracket 57, Figs. 1 and 2, by means of clamps 58. The base or bottom of the U-shaped bracket passes across the press at the rear. One arm of the U, on the right side of the press, is 20 extended upward and forms a support 59 for the nozzle arm pivot 60. It follows, that as the form member moves back and forth the nozzle arm with the nozzle is moved likewise and the paper, after having been 25 picked up by the nozzle, is transferred from the pile and to the platen as will be herein-after more specifically set forth. 61, 61 are cooperating stops on the nozzle arm 56 and support 59 respectively whereby the arm 30 may be swung upward into the dotted position shown in Fig. 1 and thus the nozzle moved out of the way whenever desired.

The nozzle itself comprises the supporting body 62 provided with guide ways 63. 35 In the latter slides the nozzle bracket 64 which falls in said guides by gravity until the stop 65 rests on the top of the body 62, see Fig. 4. The nozzle bracket has a foot 66 to which are secured depending ears 67, 67. 40 68 is an adjustable stop. The nozzle 69 is pivoted at 70 in the said ears and has a forwardly projecting relatively heavy head 71 and a stop 72. The nozzle 69 is hollow and provided with a pipe connection 73. The 45 nozzle head has a curved paper engaging and curling surface 74 and a straight paper pick up surface 75 formed with a shoulder 76 between the two openings or slits 77, 77. The nozzle arm 56 carries a cam roller 78 which runs on the nozzle cam 79 secured to the aforesaid cam support 30, see Fig. 9.

When the press is open the nozzle arm is in the dotted position in Fig. 9, the roll 78 being at the foot of the cam, and the nozzle 69 hangs in the position shown. When now the press closes, the nozzle arm is moved forward into the position shown in full lines in Fig. 9, and guided in its movement by the cam 79, until the supporting rod 54 has 50 reached its final forward position, where the nozzle is brought to rest upon the paper as shown in Figs. 9 and enlarged in Fig. 3. As the pile of paper decreases the nozzles drop deeper as will be understood.

55 When the nozzle comes to rest upon the

paper, the head of the nozzle is brought up against the stop 68. At this moment the suction occurs, as hereinafter explained and at the same time the press opens and the nozzle support is lifted and moves up and away 70 from the nozzle which falls as it were, see Fig. 4. The top of the body or bracket 62 abuts the stop 65 and lifts the nozzle bracket 64, thereby causing the nozzle to fall forward as shown until its stop 72 hits the foot 75 66. The fall of the nozzle around the pivot 70 causes a forward sliding movement of the top sheet of the paper—away from the leading edge. The sucking up of the paper by the two slits 77 causes a buckling or crimping of the paper against the shoulder 76. The sliding movement away from the leading edge of the paper underneath and the crimping of the sucked up sheet together causes perfect separation from the pile. 80 85

The paper is then carried in over the platen and at the proper time, the suction ceases to act, and the sheet is dropped upon the transfer table.

Before explaining the latter, I wish to 90 refer to the modified nozzle shown in Fig. 7. In this instance the shoulder 76 is absent and the bottom straight picking up surface 80 is rearwardly inclined. This nozzle is intended for use with heavy paper or cardboard where crimping is not possible and where a somewhat more accentuated bending of the sheet is desirable. 95

Transfer table.

The transfer table, Fig. 8, comprises an upper rod 81, pivoted in brackets 82 on the feed table, two side arms 83, 83 and a lower shaft 84 journaled in said side arms. The shaft 84 is constantly rotated by means of 100 the metal roller 85 fast on it and fibre rollers 86 and 87. The latter is driven from the wheel 88 on a shaft or stud 89 which also carries a smaller wheel 90, which is driven from the platen locking cam 12. The stud 110 89 is carried by an arm 91 pivoted at 92 and the wheel 90 is kept in frictional contact with the platen locking cam 12 by a spring 93.

Referring to Figs. 3 and 4 it will be seen 115 that the roller 85 and wheel 87 are relatively fixed, but that the wheel 86 runs on them by gravity in that said wheel 86 is provided with an opening 94 larger than the stud 95 on which said wheel is carried. The wheels 120 86 and 87 are in turn supported on the plate 96 which is slotted at 97 and which plate is adapted to swing on the shaft 84. 98 is a spring which bears against a stud 99 fast in the arm 83. Thus the wheel 87 is kept 125 down upon the wheel 88 by the spring 98 and the wheel 86 rests by gravity on wheel 88 and roller 85, whereby good frictional driving is obtained.

Referring now to Fig. 9, it will be seen 130

that the arm 83 on the right side of the press carries a cam or stop 100 pivoted on said arm at 101 and adjustable by a screw 102 and slot 103. The said arm 83 is carried by an arm 106 pivoted to the platen at 107 and connected to the upright 16 of the bracket 18 by a link 108.

The transfer table further is provided with paper supports 108, and side guides 109. The latter carry fingers 110. The whole transfer table may be swung upward and forward until it rests upon the feed table as shown in Fig. 9. This is done to get the transfer table out of the way when it is desired to examine the platen and when the feed table is raised and moved to one side as explained in the foregoing. When the transfer table is lowered as in Figs. 8 and 9, it is brought to rest on the roller 105. When the press opens or closes, the transfer table is lifted up out of the way of the platen by the arm 106 and roller 105, said arm 106 moving with the platen as shown in full and dotted lines. When the transfer table is lowered, the spring 98 on the plate 96, Figures 24 and 25, forces the plate downward, hence the wheel 87 into driving contact with the wheel 88. When the transfer table is raised the spring 98 merely forces the plate 96 into a position with the end of the slot 97. The wheel 86 will always fall into contact with the wheel 87 and roller 85 thus insuring a good drive for the shaft 84.

If a short sheet is fed, it is of course, desirable to have the transfer table lowered as much as possible so as to have the distance between the shaft 84 and the platen as small as possible and consequently the cam or stop 100 is adjusted so that it will not touch the edge of the feed table and keep the transfer table out of contact with the lifting roller 105. When a longer sheet is fed, it is desirable to increase the distance between the shaft 84 and the platen and the cam 100 will in that case be adjusted so that when the transfer table is in its lowermost position, the said cam 100 will abut the edge of the transfer table and keep it the desired distance away from the platen and in that case, when the platen moves up, the roller 105 will simply be moved out of contact with the lip 104.

To sum up: The transfer table bridges between the feed table and the platen. The transfer table is moved up out of the way by the arm 106 and roller 105. When the transfer table moves down it will continue to rest on the roller 105 except in the case of long sheets, when the transfer table will not be lowered on the roller 105, but the latter will move down away from the transfer table and the latter will only move as low as permitted by the cam 100. The

sheet is dropped upon the transfer table and is run off onto the platen by the swiftly rotating shaft 84.

The gripping mechanism.

See Figs. 10 to 17 inclusive, also Figs. 31 and 32. Secured to the feed tables are two rods, preferably square in cross section, and number 110 and 111. The gripper carriage 112 slides on said rods, which thus serve to support the gripper mechanism. The gripper carriage slides on the rod 110 by means of a suitable jaw or forked bearing 113, Figs. 10 and 32, and slides on the rod 111 by means of guide rolls 114, 114, supported on the gripper carriage by suitable means or plates 115. Underneath the latter, Fig. 17, there is pivoted at 116 a latch 117 which projects beyond the end of the gripper carriage as shown, Fig. 16. The latch 117 is urged downward by a small coiled spring 118 inserted between the latch and underneath the lower plate 115. The latch is adapted to snap into engagement with a sliding bearing 119 which moves on a rod 120. The sliding bearing has a cut out portion 121, see Fig. 12, into which the latch drops, and sloping approaches or cam portions 122, 122. The bearing 119 is further provided with a stud 123 to which is pivoted the gripper carriage operating link 124, the other end of which is pivoted at 125 to the frame 126 of the inking mechanism 9, see Fig. 1.

From this it will be seen that no matter in what position the gripper carriage may be with respect to the bearing 119, when the latter commences to move on the rod 120, as when the press is running, the bearing will move under the latch and the latch will drop into the bearing. In moving under the latch the sloping approaches 122 will first lift the latch up, so that the bearing can pass under the same. Thereafter the gripper carriage will be reciprocated corresponding to the operation of the press by the link 124.

This feature of detachably connecting the gripper carriage from the operating link 124 is necessary when it is remembered that at times the feed table, hence the gripper carriage, is lifted and the press bearings operated by hand feeding or for repairs or other reasons. During such operation the link 124 will reciprocate the bearing 119 and when it stops it may or may not be in the exact position underneath the gripper carriage (which latter will have been moved forward or to the left in Fig. 11). The re-engagement of the bearing 119 and the gripper carriage is, however, automatically completed by the bearing moving under the latch as described.

The gripper carriage is drawn forward when the feed table is raised by the follow-

ing means. On a rod 125, Figs. 10, 11 and 15, secured to the feed table, slides a spring 126 which bears against the underside of the feed table frame 24. There is sufficient tension in said spring to maintain it in any position to which it may be moved. The spring has a nose 127 which projects in the path of the gripper carriage 119 or the plate 115 thereof. 128 is a tape connected to said

10 spring which passes over a roller 129 and is attached to the curved lever 28, see Fig. 9.

When the said lever is swung down to raise the feed table, the latch 117 is of course at once disengaged from the slidable bearing 119 and as the lever moves down, the spring 126 is pulled to the left by the tape 128 and carries the gripper carriage with it. When the table is again lowered, the bearing 119 will engage the latch and carry the gripper carriage rearward, to the right, in regular operation, whereby the spring 126 will again be moved to its normal position.

Returning now to the gripper mechanism, the gripper itself is numbered 130 and comprises a relatively fixed lower jaw 131 and a movable upper jaw 132 connected by a toggle joint 133. The lower jaw is carried by a clamp 134 secured to the carriage 112. The upper jaw is opened and closed upon

30 the lower jaw by means of a gripper operating link 135 connected to the toggle joint 133 and adjustably pivoted at 136 to an arm 137 in turn adjustably carried on a gripper shaft 138 by a set screw 139. From this it is clear that the gripper may be adjusted sideways by sliding the clamp 134 on the carriage 112 and by sliding the arm 137 on the shaft 138. The shaft is supported in bearing 140 and a spring 141 tends to turn

40 the shaft in a clockwise direction to close the gripper. On the gripper shaft is fixed an arm 142 bearing a roller 143. 144 is a gripper latch and opening means and consists of a narrow strip of metal pivoted at

45 145 and having a gripper opening finger 146 and a latch piece or portion 147. 148 is a spring which tends to force the opening finger 146 upwards. On the feed table frame is secured a closing roller 149 and on a rod

50 150 is adjustably mounted a gripper opening cam 151 by means of a set screw 152.

During the operation of the press, the gripper carriage is moved forward to the left in Figure 10, when the press closes and vice versa. At the end of the rearward movement (to the right in Fig. 10) the opening finger 146 abuts the opening roller 149 and is depressed, the tail piece or latch 147 is moved upward and the shaft 138 is turned quickly by the spring 141 in a clockwise direction. Hence the arm 137 is likewise moved to straighten out the toggle joint and the upper gripper jaw closes with a snap upon the lower jaw which has moved in

65 under the paper on the platen, see Fig. 9.

The gripper is thereafter moved forward and carries the printed sheet in under the feed table. At the proper time, depending upon the size of paper printed, the roller 143 moves under the opening cam 151 and the arm 142 is depressed, consequently the gripper shaft 138 is moved in an anti-clockwise direction and the gripper is opened and the sheet dropped. As the arm 142 is depressed, the catch 153 thereon snaps above the latch 146 and is held by the latter until the gripper is closed. When the gripper is closed, the latch 147 snaps above the catch 153 and thus serves to maintain the gripper in respectively open and closed positions. The printed sheet is delivered or dropped from the gripper onto the receiving board 160 and is jogged or stacked in a neat pile by the

Stacking mechanism.

This mechanism is illustrated in detail in Figs. 18 to 23 inclusive.

The receiving table or board 150 is suitably secured to the frame of the press beneath the feed table and immediately in front of the platen. The table 160 is provided with longitudinal guide slots 161, 161, and transverse guide slots 162, 162. Secured to the table 160 are two guides 163, 163. 164 is a very thin plate which may be adjusted by hand in the guides 163 and which carries two yielding front stop fingers 165, 165 pivoted to said plate 164 and held by springs 167.

Pivoted to the platen rocker bearing 170 are two links 172. The other ends of said links 172 are pivoted to a jogger cam plate 173 provided with jogger cams 174, one on each side. The jogger cam plate further carries a rear jogger 175 having vertical slits 176 to enable said rear jogger to be moved forwardly a distance over the fixed curved paper guides 177. 178, 178 are posts which slide in the aforesaid guide slots 161 and which also support the rear jogger 175 as shown.

The numerals 179, 179 denote side joggers which are carried by posts 180, 180, adapted to be adjusted in slides 181, 181 by wing nuts 182, 182. The slides 181 are movably supported in guides 183, 183. The slides further carry each a cam roll 184. The cam rolls are held against the cams 174 by a spring 185.

The printed sheet is dropped from the gripper down upon the receiving table. In falling on said table, the paper slides forward over the curved guides 177 and towards the stops 165. This happens at the moment when the press opens, consequently the cam plate 173 is moved forward, with the front jogger 175, which pushes the paper against the stops 165 and jogs the pile together longitudinally. As the plate 173 and cams 174 move forward, the cam rolls 184

move inwardly on said cams and carry the slides 181 and the side joggers 179 along, so that the pile is jogged or evened by said side joggers.

- 5 The stroke of the rear jogger 175 is fixed by the movement of the platen rocker bearing 170. The forward stops 165 may be adjusted by moving the plate 164 with the stops 165, and the adjustment of the side joggers 179 is effected by adjusting the position of said joggers in the slides 181 whose movement is fixed.
- 10

The movements of the several above mentioned parts of the mechanism is coordinated with the movement of the press, so that as the latter opens, the suction nozzle 53 deposits a sheet on the platen. The sheet is then printed and when the press opens, the gripper moves toward it, seizes the sheet, moves forward and deposits the sheet on the receiving table and so on. When it is desired to hand feed the press, the feed transfer table is thrown up on the table, the latter is lifted whereby the gripper mechanism is detached from the operating link 124. Thereafter the feed table is moved to one side and the press may be hand fed, the jogging mechanism stacking the paper as the operator drops it onto the receiving table.

30

Tripping mechanism.

Means are provided for tripping the form or tripping the press as it is usually stated. In this instance, means are provided for 35 operating the usual tripping lever 14 to actuate the usual tripping mechanism on the press in case the suction nozzle fails to pick up a sheet and feed it to the platen, and in case the gripper fails to remove the printed sheet from the platen. See Figs. 1, 2, 10 and 26 to 33 inclusive.

Referring to Fig. 1, the form 190 is as usual connected to an eccentric shaft 191 by means not shown. 192 is an arm secured 45 to the shaft and which arm is connected by a link 193 to another arm 194 fast to a shaft 195. The latter is provided with a slotted arm 196. 197 is a pin which plays in the slot in the arm 196 and which pin is fast in a locking arm 198 mounted on a second shaft 50 199. Outside the frame the shaft 199 carries an arm 200 connected by a link 201 to the tripping lever 14 which is pivoted at 202. All of the foregoing is well known in the 55 art.

When the tripping lever 14 is thrown by the operator—to the left in Fig. 1—the shaft 199 is rotated anti-clockwise. The shaft 195 is rotated clockwise. The link 193 is lifted and swings the arm 192 upward, thereby rotating the eccentric shaft 191 to withdraw or trip the form 190, all in a well known manner.

The present automatic tripping and untripping mechanism comprises the follow-

ing elements. See Figs. 26 to 33 inclusive. To the bottom of the tripping lever 14 is pivoted a head 210 by means of a stud 211. The head is provided with a slot 212. 213 is a trip cylinder secured to the head 210 by screws 214. Within the cylinder there is a plug 215 having a shoulder 216. 217 is a spring urging the plug outward. The cylinder is connected by a hose 218 to the pump 219, and is provided with a slot 220 75 adapted to receive the latch 221 which is pivoted on said cylinder 222. The latch is urged inward in said slot 220 and against the plug 215 by a spring 223. The latch also carries a roller 224 and is operated by 80 the tripping link 225 which is pivoted to the U-shaped bracket or frame 57 at 226, see Fig. 1.

The link 225 is adapted to slide in the slot 212 in the head 210 and is provided with 85 a shoulder 228 adapted to take against the shoulder 216 on the plug 213 and a ledge 229 whereby said link is kept occupying the full depth of the slot 212 as will be understood from Fig. 28. The link carries 90 a fixed unlatching finger 230 and a movable unlatching hook 231 pivoted at 232 and adapted to be operated by a magnet 233. The finger 230 is adapted to contact with the roller 234 to depress it so as to move the 95 latch out of the slit 220. Similarly, the hook 231 is adapted to contact with a post 234 on the latch to lift the latter to the same effect. 235 is a slot in the link 225 and 236 a button or projection.

Mounted on the frame of the press is an air release 240, Fig. 31, comprising a fixed bracket 241 having an air hole 243 connected to the pump by hose connection 243. Pivoted on said bracket at 244 is an arm 245 105 having a hole 246 through which a link 247 is adapted to slide. The link has a notch 248 and the arm has a lever 249. The latter has a pin 250 which passes through a hole in the arm 245 and into the hole 246 110 through which the pin is adapted to enter the notch 248 in the link 247. The lever 249 is pivoted at 251 and a spring seated pin 252 acting against the short arm 253 of the lever 249 normally keeps the pin 250 down 115 in engagement with the notch 248 in the link 247. 254 is an eye in the lever 249 connected by a chain 255 to a switch lever 256. The pump 219 is pivoted to the floor at 257 and the piston rod 258 from the pump piston is 120 connected at 260 to the gear 261 on the press.

Referring now to Fig. 1, it will be seen that if the suction takes place through the hose 300, the nozzle 53 picks up a sheet. Suction then also occurs in the trip cylinder 125 213, whereby the plug 215 is sucked or moved inwardly and the latch 221 under influence by the spring 223 snaps in front of the plug and rests against the shoulder 216 thus keeping the plug away from the trip 130

operating link 225 which as the press opens slides idly in the slot 212 in the head 210. The sheet is then deposited on the platen as air is permitted to enter below the pump piston as will be presently explained.

Next the press closes for printing and the link 225 moves through the head. Immediately after the shoulder 228 on the link has passed the plug 215, the fixed finger on the link hits the latch roller 224 and unlatches the plug, which thereupon is moved out by the spring 217 and now rests against the surface of the link 225. After printing the press again opens and if suction occurs, the above mentioned operation is repeated and the link 225 has at no time been in operative connection with the tripping lever 14.

That is to say, normally the plug 215 projects into the path of the shoulder 228 on the link 225 and if it remained in that position the shoulder 228 would catch said plug and move the tripping lever and trip the press. But because the suction operates properly, the plug is sucked out of the path of the shoulder 228 and latched. But as soon as the said shoulder has passed the plug, the latch is operated by the link finger 230 to unlatch the plug which then moves outward ready for the next operation. And inasmuch as the tripping mechanism has not operated, the air release 240 remains undisturbed.

If, however, the suction fails to act so that air enters through the nozzle 53, the plug 215 will remain in its projected or outward position as shown in Fig. 28. Consequently, when the press is closed for printing, the shoulder 228 on the link 225 will catch said plug, that is, the link will become operatively connected with the tripping lever and throw the latter, thereby tripping the press, and at the same time, the operation of the tripping mechanism will cause the shaft 199 therein to be rotated anti-clockwise as explained and through an arm 260 fast on said shaft, the link 247 connected to the air release will be operated and the arm 245 thereof will be moved forward on the pivot 244 and the air hole 242 will be uncovered and air will pass into the pump. Continuing the operation of the press, on the opening stroke, the button 236 on the link 225 will abut the head 210 fast to the tripping lever and carry the latter back to position, thereby untripping the press. On the next stroke, the press will again be tripped, because air having entered through the air release, suction will again fail, so that after one tripping because of failure of the suction, the press will continue tripping until the cause of the trouble is located and attended to and the air release set to cover the air opening 242.

65 The air release is set or rendered inactive

as follows. When the operator discovers that the press is tripping, he lifts the switch handle—or whatever other element the chain 255 is attached to—thereby lifting the lever 249 and lifting the pin 250 out of engagement with the socket in the link 247. The latter will therefore no longer operate the arm 245 to uncover the air hole. The arm 245 is moved into normal position by the collar 261 on the link 247, Fig. 33.

75 The tripping mechanism is also arranged to trip automatically in the event that the gripper fails to take a sheet from the platen, as for instance when the sheet is torn and cannot be reached by the gripper or for other reasons. In this case the unlatching of the latch 221 so as to permit the plug 215 to move into the path of the shoulder 228 on the link 225 is done electrically in advance of the movement of said shoulder.

85 Accordingly, an electric circuit is established on the press comprising the following elements. A thin strip of brass 265 is attached to the movable jaw of the gripper, but insulated therefrom as seen in Fig. 31. A wire 266, Fig. 10, passes from said gripper contact 265 to a contact 267 on the gripper carriage, Fig. 32. During the operation the contact 267 slides against a brass spring contact 268 carried by the feed table 90 and which makes contact with a spring seated button 269 carried by the frame. From the button a wire 270 leads to the battery 271. Fig. 32, merely illustrates the manner in which the circuit is established 100 between the feed table and the frame. If the feed table were not arranged to be swung away from the frame, the parts illustrated in Fig. 32 might be omitted.

105 In Fig. 31, the contacts 267 and 268 are shown diagrammatically and the circuit is as follows. From the battery 271, wire 270, contacts 268 and 267, wire 266 to the gripper contact 265. From the other side of the battery, to the switch 256 to the magnet 110 233 and to ground on the frame.

When the gripper moves in over the platen to take a sheet, contact is established between contacts 267 and 268. If there is no sheet on the platen for the gripper to take, 115 closing of the gripper establishes the circuit as follows.

120 From battery to gripper contact 265, through the frame to the magnet 233 to the switch and back to the battery. Consequently the magnet is energized and when the press closes for printing, the hook 231 will be in the path of the post 234 on the latch, lift the latter away from the plug 215 which will be caught by the shoulder 125 228 and the press tripped. This in turn operates the air release and prevents further feeding of the paper to the platen. Thereafter the switch is opened to reset the air release and break the circuit. The trouble 130

is thereafter attended to. The press then commences to operate again and the switch is left open until after one sheet has been fed to the platen, after which the switch is closed. If the switch is closed sooner, the press will again be tripped because there is then no sheet for the grippers to act upon.

Means is further provided for adjusting the release of the sheet from the nozzle at 10 the right point over the platen depending upon whether the sheet is long or short. See Fig. 2. The pump piston is apertured at 270. A pivoted cover 271 covers the hole 270. 272 is an adjustable stop depending 15 through the pump top. On the suction stroke of the piston 259 the cover 271 will be depressed by the stop when the latter is reached, the air hole will be uncovered and air admitted below the piston, consequently 20 the sheet will be released from the nozzle.

It will be seen from the foregoing that automatic separating and feeding has been provided for. That automatic gripping and delivery as well as stacking takes place automatically. Also, that in the event the suction or the gripping mechanism does not function to respectively feed and take a sheet, the press will be automatically tripped.

30 All of the said mechanisms are attached to the press without any material alterations thereof except the boring of a few holes for securing brackets and the like. And as shown, the suction means and 35 the entire feed table and gripping mechanism may be swung aside in an instant and the press be ready for hand operation.

While operating by hand there is of course no suction and consequently the plug 215 in 40 the trip cylinder would remain in the path of the shoulder on the link 225 and the press tripped constantly unless some provision is made to the contrary. Accordingly, there is pivoted at 275 on the tripping lever 14 45 a link 276 having a hand grip 277. The link 276 is at its bottom, see Figs. 27 and 28, pivoted to a bell crank 278 pivoted at 279. The bell crank 278 has a nose 280 adapted to engage a pin 281 which in turn 50 is designed to contact with the plug 215. When operating the press for hand feeding, the hand grip 277 is tied down as it were to the gripping lever by a ring or loop 283 to lift the link 276. This in turn operates 55 the bell crank 278 and the nose 280 thereof moves in pin 281 inwardly and pushes the plug 215 back into the cylinder 213. Thus during hand operation, the plug is kept 60 permanently out of the way of the tripping shoulder 228 and as the link 225 moves with the form member of the press, it slides idly past the tripping lever without tripping.

If the operator desires to trip the press he throws the tripping lever as usual. In Fig. 65 28 parts of the bell crank 278 are shown

dotted for the sake of clearness. To facilitate the separation of the top sheet a nozzle 290 is provided which is connected to the pump by a hose 291 and blows a blast of air on the pile of sheets 52.

The foregoing is thought to clearly set forth the construction of the various mechanism whereby a platen press may be made wholly automatic in operation. It is of course understood, that nothing herein is intended as a specific limitation, but that changes and modifications may be made in the detailed construction without departing from the principle of the invention or the scope of the appended claims.

I claim.

1. In a printing machine, means for supporting the paper to be printed in an inclined position thereon, means for lifting said paper supporting means longitudinally 85 of said machine into a position away from operative relationship with the said machine, and mechanism permitting said paper supporting means to be moved in a horizontal plane away from the said printing machine. 90

2. In a printing machine, paper supporting means adapted to rest in a given position on said machine, mechanism for moving said supporting means upward into a substantially horizontal plane, means for locking the said paper supporting means when it rests in said given position and when it is moved upward and means permitting said paper supporting means to be swung to one side clear of the said printing machine. 100

3. In a printing machine, paper supporting means, means for pivoting the same in the said machine, means for locking said paper supporting means in normal position 105 in said machine, means for operating said supporting means in the said pivot to lift the said supporting means out of said normal position and mechanism carried by said pivoting means permitting said paper supporting means to be moved to one side in a substantially horizontal plane away from operative relationship with the said machine. 110

4. In a printing machine, brackets secured to the frame of said machine, a support pivoted on one of said brackets, paper supporting means carried by said support, means for operating the latter to cause said paper supporting means to rest on the said brackets and for moving said paper supporting means away from said brackets and mechanism for swinging said paper supporting means on the said support to one side of the said machine. 115

5. In a printing machine, a paper feed table, a paper transfer mechanism pivoted on the said table and adapted to be swung upward to rest thereon, paper registering means on said feed table and mechanism for 120 125 130

moving said feed table upward longitudinally of said machine and thereafter to one side clear of the said machine.

6. In a printing machine, paper supporting and registering means, paper gripping and delivery means, a feed table frame for supporting all of the aforesaid means and mechanism for pivoting the said feed table on the said machine to move said feed table into or out of a given position with respect to said machine, and means for locking said feed table in both of the said two positions.

7. In a printing machine, a pair of brackets secured to the frame thereof, said brackets having supporting shoulders, a feed table pivoted to one of said brackets and adapted to rest upon the supporting shoulders thereof, and mechanism for lifting said feed table upward away from the said supporting shoulders and moving said feed table on the said one bracket sideways away from the said machine.

8. In a printing machine, a movable form member, a feed table, gripping mechanism carried by said feed table, a link pivoted on said movable form member and detachably engaged with said gripping mechanism to operate the same on said feed table and means for moving the latter upward and simultaneously therewith disengaging said gripping mechanism from the said link.

9. In a printing machine, a movable form member, a feed table, gripping mechanism carried by said feed table, a link pivoted on said form member and detachably engaged with said gripping mechanism to operate the same on said feed table and means for moving the latter upward and simultaneously therewith disengaging said gripping mechanism from the said link, and means on said gripping mechanism for automatically engaging with the said link when said feed table has been lowered.

10. In a printing machine, a movable platen, and a movable form member, a gripping mechanism, means for supporting said gripping mechanism in cooperative relationship with said platen, a link secured to said form member for operating said gripping

mechanism, means for raising said gripping mechanism away from said platen and automatically disengaging said mechanism from the said operating link.

11. In a printing machine, a platen, a feed table, a gripping mechanism supported on the same, a gripper carriage adapted to move towards and away from said platen, means for operating said gripper carriage, mechanism for raising said feed table and said gripper mechanism and simultaneously therewith engaging said gripper carriage from its operating means and for automatically moving said gripper carriage on said feed table in a direction away from the said platen.

12. In a printing machine, supporting means, an arm pivoted thereon, a feed table pivoted on said arm, a link pivoted on said supporting means and a lever pivoted to said lever and said arm for operating the latter to raise the said feed table away from said supporting means.

13. In a printing machine, a platen, a form member, mechanism for supporting the paper to be printed and for removing the printed sheet from the platen, separating means, means for supporting said separating means in a normally active position on the said form member, means for moving said mechanism away from said platen and means for moving said separating means into inactive position on said form member.

14. In a printing machine, a platen, a form member, paper supporting mechanism, paper gripping mechanism, means for supporting the said two mechanisms in normal active positions with relation to the said platen, paper separating mechanism, means for supporting the latter on the said form member in a normal active position relative to the said paper supporting mechanism and the said platen, means for moving said supporting and gripping mechanisms into inactive position relative to the platen and means for moving said separating mechanism into inactive position on said form member.

LEWIS E. MORRISON.
